UNITED STATES PATENT OFFICE.

EUGENE FONTAINE, OF WAGON WORKS, OHIO.

RAILWAY-CROSSING.

SPECIFICATION forming part of Letters Patent No. 355,156, dated December 28, 1886.

Application filed September 23, 1886. Serial No. 214,347. (No model.)

To all whom it may concern:

Be it known that I, EUGENE FONTAINE, of Wagon Works, in the county of Lucas and State of Ohio, have invented new and useful 5 Improvements in Railway-Crossings; and I hereby declare that the following is a full, clear, and exact description thereof, reference being had to the accompanying drawings, which form a part of this specification.

10 This invention relates to certain new and useful improvements in the construction of railway-crossings, as hereinafter described.

My improved railway-crossing belongs to that class in which short rail-sections are pivotally secured at the intersections of the rails and connected by mechanism whereby they may be turned simultaneously to register with either track to form a continuous rail; but great difficulty is experienced with the construction in present use on account of their 20 great liability to become inoperative. This is frequently caused by snow and ice, which, being allowed access to the parts, often render them inoperative by freezing. A further cause 25 is the use of cogged gearing, which not only permits stones to wedge accidentally between the cogs, but is especially liable to be maliciously tampered with. Failure is also caused by insufficient protection of the working parts 30 against the filling in of the ground, and by the insufficient manner of supporting the rail-sections.

It is the object of my invention to overcome these defects, and to this end I have designed 35 the improved crossing shown in the accompanying drawings, in which—

Figure 1 is a plan with the rails omitted. Fig. 2 is a side view, partly in elevation and partly in section. Fig. 3 is a plan of one of 40 the intersections, and Fig. 4 is an elevation of the signal-post and the operating-lever. Fig. 5 is a cross-section on line $\alpha\alpha$ in Fig. 1.

A are the rail-sections of the crossing.

B are four vertical posts pivotally secured 45 at the intersection of the rails. At their upper ends these posts carry the rail-sections C, preferably formed integral with the posts.

G is the rail-support of the crossing. It represents a four-sided curb with circular enlargements at the corners, all so arranged that 50 the straight sides of said curb form a strong

continuous supporting-girder under the stationary rails of the crossing, while the circular enlargements at the four corners form corner curbs, which, in connection with top and bottom plates, afford a firm support and protection for the corner-posts at the intersections of the crossing. 55

The construction of the curb is as follows: A girder, *a*, having the cross-section of a so-called "channel-iron," and made in four pieces, bolted together at the ends, forms the four sides of the curb, together with the circular enlargement at the corners. Each of the four sections of the girder forms the straight portion of one side and one-half of the circular enlargements at the two adjacent corners. To the inner side of this girder, and near the top and bottom edges thereof, are secured the angle-irons *b*, except at the corners where they 60 complete the circular enlargements on the inside and form the remaining portion of the corner curbs in such a manner as to leave an opening, *c*, for an access to the interior of the well between them. The circular corner wells 65 formed by the supporting-girder are closed on top and bottom by plates *d*, secured thereto, and by means of clips *e* the ends of the rails are secured to the top plates. These clips have segmental circular flanges *f*, which form 70 a protecting-wall around the exposed upper ends of the posts and facilitate the application of a lubricant. 75

The posts B have shoulders *h*, which furnish a support upon the top plates, and they are supported laterally by the top plates, through 80 which they pass, and by means of steps *g*, formed on the bottom plates. The movable rail-sections carried by the posts are preferably formed integral with the posts, which are just 85 sufficiently cut away upon opposite sides at the top to form the head of a rail and permit the flanges of the wheels to pass. This construction, in case of a wrong crossing, reduces the danger to a passing train. 90

D is a signal-post of known construction and operation, E being its operating-lever. This signal-post is placed near the track, in line, or nearly so, with one of the diagonals of the crossing. To the lower end of the staff of the signal-post is secured a crank-arm, *i*, to which 95 the connecting-rod *j* is secured, which connects 100

the crank-arm *i* with another crank-arm, *k*, secured upon the nearest post. Another connecting-rod, *l*, connects said crank-arm *k* with a crank-arm, *m*, secured upon the post diagonally opposite the first. Upon each of the posts so connected are secured additional crank-arms, *n o*, to which connecting-rods *p q* are pivotally secured to connect these posts in a similar manner with the remaining two posts, all so arranged that by the proper movement of the operating-lever *E* all the posts are rotated simultaneously in the desired manner.

The stationary rail-sections of the crossing are supported at the end, as before described, on the top plate of the corner wells, and intermediate between they are supported on corrugated bars *r*, which are inserted between them and the top of the supporting-girder. This construction lessens the noise and the destructive action on the supporting-girder caused by vibration.

The whole crossing is supported, as usual, on sleepers placed in suitable number and positions underneath the structure.

It will be observed that, in addition to the aforementioned advantages sought to be derived by my construction, the additional advantage is obtained that I avoid the use of large and unwieldy castings. Further, the operating parts, although easily accessible for the purpose of inspection or repair, are all inclosed within a curb and well protected, and thus less liable to fail on account of accidental or malicious interference.

What I claim as my invention is—

1. In a railway-crossing having rotatable posts at the intersections, a continuous rail-support in the form of a four-sided curb with circular enlargements at the corners, substantially as described.
2. In a railway-crossing having rotatable posts at the intersections, the combination, with a continuous supporting-girder forming circular wells at the corners, of top and bot-

tom plates inclosing said circular wells, substantially as described.

3. In a railway-crossing having rotatable posts at the intersections, a continuous rail-support in the form of a four-sided curb with circular enlargements at the corners, the same consisting of the channel-bars *a* and the angle-bars *b*, connected as described, to form openings from the central well into the corner wells, substantially as specified.

4. In a railway-crossing having rotatable posts at the intersections, the combination of the continuous rail-support *C*, having circular enlargements at the corners, the top and bottom plates inclosing said circular enlargements, and the corrugated plates *r*, intermediate between the corners, substantially as described.

5. In a railway-crossing having rotatable posts at the intersections interconnected with each other by cranks and connecting-rods, the combination, with a main connecting-rod diagonally connecting two posts, of two connecting-rods connecting each of the posts thus connected with one of the remaining two posts, respectively, substantially as described.

6. In a railway-crossing having rotatable posts at the intersections interconnected with each other by cranks and connecting-rods, the combination, with a continuous rail-support forming a central well with circular enlargements at the corners communicating therewith, and wherein the posts are pivotally secured, of a main connecting-rod diagonally connecting two of the posts, and of sub-connecting-rods connecting each of the posts thus connected with the two remaining posts, respectively, all arranged substantially as described.

EUGENE FONTAINE.
